Primary Examiner — Cynthia Underwood(74) *Attorney, Agent, or Firm* — Renner, Otto, Boisselle & Sklar, LLP**CLAIM**

The ornamental design for a bread basket, as shown and described.

DESCRIPTION

FIG. 1 is a perspective view of a bread basket showing my new design;

FIG. 2 is a bottom view of the bread basket;

FIG. 3 is a front view of the bread basket, the rear view being a mirror image thereof;

FIG. 4 is an end view of the bread basket, the opposite end view being a mirror image thereof; and,

FIG. 5 is a top view of the bread basket.

The broken lines in the drawing illustrate environmental matter and form no part of the claimed design.
